UNITED STATES PATENT OFFICE.

WILLIAM H. SMYTH, OF BERKELEY, AND KARL I. FAUST, OF SAN FRANCISCO, CALIFORNIA, ASSIGNORS, BY DIRECT AND MESNE ASSIGNMENTS, TO THE FAUST MENUGRAPH COMPANY, OF SAN FRANCISCO, CALIFORNIA, A CORPORATION OF CALIFORNIA.

MENUGRAPH.

SPECIFICATION forming part of Letters Patent No. 691,013, dated January 14, 1902.

Application filed October 11, 1900. Serial No. 32,785. (No model.)

To all whom it may concern:

Be it known that we, WILLIAM H. SMYTH, residing at Berkeley, county of Alameda, and KARL I. FAUST, residing at San Francisco, in the county of San Francisco, State of California, citizens of the United States, have invented certain new and useful Improvements in Menugraphs; and we do hereby declare the following to be a full, clear, and exact description of the same.

This invention relates to a menugraph or device adapted particularly to producing printed menus or bills of fare in accordance with the improved method set forth in application filed simultaneously herewith.

The object of this invention is to provide a simple, convenient, and easily-operated device especially designed to carry into effect the method of preparing and printing bills of fare, as set forth in the application filed simultaneously herewith. We accomplish this object by means of the devices illustrated in the accompanying drawings, in which—

Figure 1 shows a plan view with the inking-plate removed. Fig. 2 is a longitudinal section through line A B of Fig. 1. Fig. 3 is a transverse section through line C D of Fig. 1. Fig. 4 is a detail of carriage-stop 35 and card-holder 29. Fig. 5 is a detail of stop 33. Fig. 6 is an enlarged detail of pressure-cylinder 10, showing the spring-pressure device for inking-roller. Fig. 7 is a detail of a portion of one of the drawers containing the numbered logotype-cells. Fig. 8 is a detail showing a modification of the inking-roller attachment.

Referring to the accompanying drawings, 1 is a cabinet of suitable form provided with drawers or receptacles 2. These drawers are preferably so made that they may be drawn out on either side of the cabinet to more than half their length in the direction of their motion. This is arranged for as shown in Figs. 2, 3, and 7. These drawers are provided, as shown in the said figures, with strips, guides, or tenons 3, extending across the ends of the drawers, but divided into two pieces approximately half of the drawer, one portion being at a lower level than the other, as shown in Fig. 7. These strips 3 slide in grooves 4 in

the interior surface of the cabinet-walls, as shown in Figs. 2 and 3. The grooves 4 do not extend entirely across the wall of the cabinet, but stop, as shown in Fig. 3, a short distance from one of the ends of the wall, thus forming a stop limiting the withdrawal of the drawers. These drawers are divided into cells 5 for the reception of logotypes.

Each logotype-cell is provided with a designating number or character 6, as shown in Fig. 7, and the logotype contained therein is also provided on one of its sides with a number or character corresponding to that on the logotype-cell.

On the upper surface of the cabinet is provided a bed 7 for the reception of the logotype-form. Suitable means, (shown in Figs. 1 and 2,) as a pair of wedges or a quoin 8, are provided for securing the logotype-form in position.

Tracks or guideways 9 are provided with a reciprocating frame or carriage, to which is journaled an impression-cylinder 10. This cylinder 10 is provided with a segmental or mutilated impression-surface, and eccentrically journaled to the cylinder opposite the mutilated portion of the impression-surface is the inking-roller 11. The inking-roller is arranged parallel to the axis of the cylinder 10 and is journaled within the peripheral line of the segmental impression-surface, so that in its normal position its periphery is substantially coincident with or projects slightly beyond the peripheral line of the impression-surface. This roller 11 is preferably connected so as to provide for a yielding resistance. This is secured by the following means: The inking-roller rotates freely upon a non-rotatable axle 12, transversely perforated at 13 near each of its ends. Through each of these perforations passes a rod 14, which are radially secured to the impression-cylinder 10. Around each of these rods 14 is a coil-spring 15, bearing against the axle. The rods 14 are also provided with threaded ends having lock-nuts 16 to limit the outer motion of the wheel-axle, the inward motion of the wheel-axle being yieldingly resisted by the springs 15. A modification of this roller con-

nection is shown in Fig. 8, in which the nuts on the rods 14 are omitted, their place being taken by the latch-spring 16^a and the rod 14 being secured in the axle and moving down 5 with it.

The cylinder 10 is provided at both of its ends with a concentric mutilated gear 17, the teeth of which extend around nearly the whole of the circumference at a point on the periphery commencing near the roller 11 on one side and ending near this roller on the other side, leaving a segment-blank of teeth in the space occupied by the inking-roller 11. Between the ends of the geared portion of this toothed 15 wheel 17 is a flattened portion 18. A spring-latch 19 is provided on each side of cylinder 10 and attached to the frame 20, in which the cylinder 10 is journaled. A stop 21 on the side of cylinder 10 is provided to engage with 20 the latch 19. A rack 22, secured upon the guides or ways 9, is provided, into which meshes the geared wheel 17. The length of 25 the rack 22 is substantially the same as the length of the geared portion of the wheel 17, and a plane untoothed portion 23 extends beyond the rack. Upon the top of the cabinet between the untoothed portion of the rack 22 is an inking-plate 24, adapted to rotate in a horizontal plane. Its upper surface is in sub- 30 stantially the same plane as the printing-surface of the logotype-form. The spindle 25 of this inking-plate is provided with a ratchet 26 and a pawl 27. A cam-lever 28 is provided, pivoted at one end, the other end being loosely 35 connected to the pawl. Cam-lever 28 is in the path of the carriage 20, to be operated thereby.

A frame for holding the card or other matter to be printed upon is provided, consisting 40 of parallel strips 29, one on either side of the bed or form-holder. Each strip rests upon springs 30 and is provided with pin-and-slot connections 31. These strips may be connected by light wires 32. This frame is shown 45 clearly in Figs. 1, 2, and 3 and particularly in the detail Fig. 4.

A trip or spring latch 33 is provided in the path of the carriage 20 adjacent to the gears, suitably placed to engage with the end 34 of 50 the flattened portion 18 to insure engagement of the gear-teeth 17 with the rack 22. At the opposite end of the gear-rack 22 is provided a raised lug or projection 35 in a similar relative position as the spring-latch 33, which 55 also engages with the end 34 of the flattened portion 18, forming a limiting-stop to the travel of the carriage.

A clip or holding-piece 36, consisting of a flat-headed pin resting upon the parallel 60 strips 29, is provided to hold the sheet or card in position while being printed.

Ball-bearings 37 are provided between the frame and the track to reduce the friction.

The operation of the device is as follows: 65 The drawers of the cabinet opening on either side permit access to the contents on either side of the cabinet, making the contained logo-

types easy of access. The strips 3 with their stops prevent the entire withdrawal of the drawers, and thus entirely guard against accidental falling of the drawers—a contingency very likely to occur without this provision owing to the great weight of metallic type or logotype. The numbering of the logotype-cells greatly facilitates the finding of the logotype, avoiding the necessity of reading the printing-surface. The bed being removable permits bills of fare relating to various meals to be set up and made interchangeable, thus saving much time in the production of bills 80 of fare. The logotype-form being set up in the bed and the bed being properly arranged in place, the cylinder 10, with the inking-roller 11 downward, is passed over the inking-plate 24, in rolling contact therewith. The cylinder 10 during this motion is prevented from rotating by the flattened portion 18 engaging with and sliding on the untoothed part 23 of rack 22. Having passed over and transferred ink from the inking-plate 24 to the 85 inking-roller 11 it continues its journey backward till the end 34 of the flattened portion 18 meets spring-latch 33, which insures the engagement of the circumferential gear-teeth with the rack 22. Thus the impression-cylinder 10 rotates over and in contact with a sheet or card previously placed on the connecting-wires 32 of the frame 29, thus pressing the card in contact with the logotype which has been inked by a previous operation of the 90 roller, and so by continued rolling of the impression-cylinder 10 it prints the bill of fare. Having passed over the card the end 34 of the flattened portion 18 comes in contact with stop 35, thus bringing the stop 21 on the side 105 of the cylinder 10 in contact with the latch-pawl 19 of the frame 20, thus locking the impression-cylinder 10 with the inked inking-roller downward, so that on its forward journey the inking-roller 11 will move over and in 110 contact with the printing-surface of the logotype, thus inking it preparatory to another printing operation. The yielding character of the inking-roller connection facilitates the operation, as it is not necessary to provide a roller of exactly a given diameter, as would be necessary if the roller did not yield. Furthermore, the roller may be considerably 115 out of true and still perform its functions satisfactorily. Another and equally desirable 120 function is provided for by the described arrangement, which is that the roller may be depressed out of engagement with the type altogether. Thus the type are readily and effectively cleaned by placing thereon a piece of 125 blotting-paper or other waste paper, and the operation of printing performed a few times under these conditions.

Still another advantage is derived from this construction in that should the printing-cylinder be accidentally left in its position over the inking-plate the inking-roller is not distorted by long contact with the inking-plate, as would be the case if no provision were made 130

for the retraction of the roller from its normal working position, the construction thus described providing a simple, convenient, and effective machine for carrying into effect the improved method of producing and printing bills of fare and other similar announcements.

It is obvious that many changes in detail of form, construction, and arrangement of the various parts may be made without departing from the essential character of this invention. It is therefore not desired to confine the invention to the exact form, proportion, or arrangements herein shown and described; but

15 What we claim is—

1. A device comprising a suitable form-receptacle and a traveling impression-cylinder containing an inking-roller located within its circumference.

20 2. A device comprising a suitable form-receptacle and an impression-cylinder containing an inking-roller located within its circumference, a sliding frame in which the impression-cylinder is journaled, movable in a plane parallel to the form-receptacle.

25 3. A device comprising a suitable form-receptacle and an impression-cylinder provided with gear-teeth on its periphery, said cylinder containing an inking-roller located within its circumference, a sliding frame in which the impression-cylinder is journaled movable in a plane parallel to the form-receptacle and a rack adapted to engage with the impression-cylinder to rotate it.

35 4. A device comprising a suitable form-receptacle and an impression-cylinder provided with a segmental gear having a flattened portion forming a chord of the gear-circle, containing an inking-roller located within its circumference, a sliding frame in which the impression-cylinder is journaled movable in a plane parallel to the form-receptacle and a rack adapted to engage with the segmental gear, provided with a toothless portion to engage with the chord portion of the segmental gear.

45 5. A device comprising an impression-cylinder containing an inking-roller within its circumference and means for rotating the impression-cylinder in one direction of its back-and-forth journey and means for locking the impression-cylinder with the inking-roller downward during the other portion of its back-and-forth journey.

55 6. A device comprising an impression-cylinder journaled in a sliding frame and an inking-roller within the circumference of the impression-cylinder and means for applying ink to the inking-roller.

60 7. A device comprising an impression-cylinder journaled in a sliding frame and an inking-roller within the circumference of the impression-cylinder and a horizontally-rotatable ink-distributing plate with means for rotating said plate.

65 8. In a printing apparatus, the combination

with a stationary printing-surface, of a revoluble impression-cylinder and an inking-roller carried by said cylinder revolubly there-with and adapted to ink the form on said bed 70 or surface.

9. In a printing apparatus, the combination with a stationary printing-surface, of an intermittently-revoluble impression-cylinder therefor, said cylinder having a segmental 75 impression-surface and an inking-roller revolubly secured to said cylinder within the peripheral line of said impression-surface.

10. In a printing apparatus, the combination with a printing bed or surface, of an impression-cylinder therefor, said cylinder having a segmental impression-surface and an inking-roller on its periphery, means for intermittently revolving said cylinder and means for intermittently locking the same 85 against revolution with the inking-roller next to the printing-surface.

11. In a printing apparatus, the combination with a bed, of a frame on said bed, said frame carrying an impression-cylinder having 90 a segmental impression-surface and an inking-roller on its periphery, interengaging gearing on said bed and said cylinder for intermittently revolving the latter and co-operating stop devices on said frame and said cylinder for intermittently locking the latter 95 against revolution with the inking-roller next to the bed.

12. In a printing apparatus, the combination with a bed, of a reciprocating carriage 100 therefor, an impression-cylinder mounted on said carriage having a segmental impression-surface and an inking-roller on its periphery, rack-teeth on said bed and mutilated gears on said cylinder for intermittently revolving 105 the latter as the carriage travels in one direction, a spring-latch on said carriage and a stop-pin on said cylinder for intermittently locking the latter against revolution as the carriage travels in the reverse direction. 110

13. In a printing apparatus, the combination with a printing bed or surface, of an impression-cylinder therefor said cylinder having a segmental or mutilated impression-surface, an inking-roller movable to and from 115 said printing-surface, means for intermittently revolving said impression-cylinder and means for intermittently locking the same against revolution with the mutilated portion of its impression-surface next to said printing-surface when the inking-roller is in contact with the latter. 120

14. In a printing apparatus, the combination with a fixed printing-surface, of a traveling carriage therefor, said carriage carrying 125 an impression-cylinder and an inking-roller, said inking-roller movable to and from said printing-surface, said impression-cylinder having a segmental or mutilated impression-surface, means for revolving said impression-cylinder during one portion of the travel of 130 the carriage and means for locking it against

revolution with the mutilated portion of its impression-surface next to the printing-surface during another portion of the travel of the carriage and when the inking-roller is in contact with the printing-surface.

15. In a printing apparatus, the combination with a form-carrying bed, of strips yieldingly secured to either side of said bed for normally holding the paper to be printed out of contact with the type-form and means for depressing said paper-carrying strips to bring the paper to be printed into contact with the type-form.

16. In a printing apparatus, the combination with a form-carrying bed, outwardly spring-pressed strips connected to said bed by pin-and-slot connections for normally holding the paper to be printed out of contact with the type-form, an impression-cylinder for de-

pressing said strips to bring the surface to be printed into contact with the type-form.

17. In a printing apparatus, the combination with a stationary printing-surface, of an impression-cylinder therefor, having an inking-roller yieldingly journaled on its periphery.

18. In a printing apparatus, the combination with a stationary printing-surface, of an impression-cylinder therefor having an inking-roller journaled thereto and movable to and from its periphery and means for yieldingly holding the roller in either its raised or depressed position.
